UNITED STATES PATENT OFFICE.

JAMES I. DEPEW, OF LOUP CITY, NEBRASKA.

POWER-HAMMER.

1,076,554.

Specification of Letters Patent.

Patented Oct. 21, 1913.

Application filed September 27, 1912. Serial No. 732,751.

To all whom it may concern:

Be it known that I, JAMES I. DEPEW, a citizen of the United States, residing at Loup City, in the county of Sherman and State of Nebraska, have invented a new and useful Power-Hammer, of which the following is a specification.

The present invention relates to improvements in power hammers.

10 The primary object of this invention is the provision of a power hammer, provided with a peculiar form of frame to which is pivotally connected the lever or movable member, one end of such lever being operably connected through a resilient connection to a rotating shaft carrying an eccentric for imparting the necessary oscillatory movement to the lever.

20 A further object of the present invention is the novel form of clutch device placed under the direct control of the operator whereby the rotating or actuating shaft is connected or disconnected to a power transmitting pulley.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 In the drawings—Figure 1 is a side elevation of the complete power hammer. Fig. 2 is a top plan view thereof. Fig. 3 is a section taken on line 3—3 of Fig. 1. Fig. 4 is an enlarged detail sectional view of the stationary and movable member of the hammer showing the adjacent portions of the hammer carrying lever and a frame. Fig. 5 is a transverse sectional view through the power transmitting pulley, and the clutch 40 actuating and clutch member thereof. Figs. 45 6 and 7 are detail views of the wedge or actuating device for the clutch.

Referring to the drawings, the numeral 1 designates the base, which has mounted 50 thereon the peculiar shaped pedestal 2, having a stationary anvil carrying portion 3, and the lever carrying arm 4. The extreme upper end of the lever carrying arm 4 is provided with the two spaced terminals 5, 55 which are in the nature of a clamp and are held together properly by means of the bolt

6 upon the sleeve 7, said sleeve 7 being so mounted as to form the pivoting or fulcrumming point for the two parallel plates or strips 8 which straddle the upper end of the arm 4 60 and constitute the walking beam or main lever of the power hammer. The two supporting plates 9 incase and are held relatively to the strips 8 by means of the two retaining bolts 8', as clearly shown in Fig. 1. 65 This connection constitutes a very important feature of the present invention, in that it properly braces and spaces the two plates 9 and provides a ready means whereby the fulcrumming point may be readily connected or 70 disconnected from the arm 4.

Connected in the outer free end of the two plates 9 and between the two fastening bolts 11 is the movable member or hammer 12, which as shown in Fig. 4 is provided with 75 the lower reduced striking end or head *a* and with the larger striking end *b*, this hammer being so constructed, as shown in Fig. 4 as to be reversible.

In the upper end of the stationary anvil 80 member carrying portion 3 of the pedestal are the respective lugs 13 which are held together upon the lower anvil member 15 by means of the clamping bolts 14, thus providing a means for the removable reception 85 of the anvil member 15 so that the same may be reversed when desired to co-act with the respective striking ends of the movable hammer 12.

Pivoted in the opposite end of the lever 90 to the end 10 between both members thereof, is a rod or bar 16 provided with the socket 17, the offset lugs 18 of the same being connected to the upper end of the leaf spring 20, while having its upper end 95 free for slight movement within the socket 17 and through the upper terminal of the leaf spring 20, is a guiding rod 21, whose lower end is threaded into the terminal 22 of the leaf spring 20 and is held in the 100 proper adjusted relation thereto, by means of the lock nut 23. Under ordinary conditions, the spring 20 is not compressed during the striking or downward action, but should the article placed upon the anvil 105 be relatively thick or cause too great resistance to the movement of the hammer, the spring will be compressed and the rod 21 will be permitted the necessary slight sliding movement of its upper end into the 110 socket 17. Upon the extreme lower end of the rod 21 is provided the eccentric strap 24,

which surrounds the eccentric 25 mounted upon the shaft 26. Thus the rotation of the shaft 26 will impart reciprocation to the rod 21, and through its connection to the leaf spring 20 impart a resilient reciprocating movement to the lever 9 so that the hammer member 12 is moved into and out of engagement with the stationary anvil 15, the sliding movement of the rod 21 within 10 the socket 17 permitting the necessary resiliency at the upper free end 19 of the leaf spring 20, and thus relieving any jar upon the eccentric 25 and its shaft 26 during the striking action of the hammer.

15 In order to provide a novel means for causing motion to be transmitted to the fast clutch wheel 27 from the belt actuated wheel 28, the clutch wheel 27 being keyed upon the shaft 26, while the transmission wheel 20 28 is freely rotatable upon the said shaft, the two wheels 27 and 28 are provided with frictional contact faces 29 and the transmission wheel 28 is so mounted as to have imparted thereto a sliding movement to and 25 from the clutch wheel 27 and having its face 30 opposed to the wedge 31, which as clearly shown in detail in Figs. 6 and 7 is provided with the elongated slot 32 which surrounds the shaft 26. Its flat face 33 30 will be moved into engagement with the flat face 30 of the transmission wheel 28 when the wedge is moved upwardly and its wedging face 34 is moved due to its sliding engagement with the inclined face 35 35 of the stationary member 35'. This action moves the clutch portion of the transmission wheel 28 into engagement, and thus the rotation of the transmission wheel 28 will

rotate the clutch member 27 and consequently the shaft 26, imparting the necessary rotation to the eccentric 25 and consequently reciprocating the rod 21.

In order to impart the necessary movement to the clutch actuating wedge 31, its lug is connected by means of the pin 36 to 40 the free end of the rod 37, whose other free end is pivotally mounted in the straps 38 and 38' carried by the pedestal 2 and presents its foot treadle portion 39 in such position as to be in ready access to the operator 45 who presents the article to be acted upon by the movable hammer 12 and its member 15, thus permitting the actuation of the double lever 9 at the will of the operator.

What is claimed is:

In a power hammer, the combination of 55 a base, a reciprocatory lever mounted thereupon, a shaft mounted upon the base, an eccentric mounted upon the shaft, a rod provided with an eccentric strap, said eccentric strap being mounted upon the eccentric, a leaf spring having one terminal connected to the rod and the other terminal of the rod being slidably mounted through the other terminal of the spring, and a bar connected to the lever and also to the last terminal of the spring, said bar being provided with a socket for the slideable reception of the free terminal of the rod.

In testimony that I claim the foregoing 70 as my own, I have hereto affixed my signature in the presence of two witnesses.

JAMES I. DEPEW.
